WALL COPING

George M. Schaulin, Akron, Ohio, assignor to
 Robinson Clay Products Company, Mogadore,
 Ohio, a corporation of Ohio

Application November 27, 1933, Serial No. 699,828

8 Claims. (Cl. 72—86)

This invention relates to wall coping of the type comprising clay sections adapted to be fitted together with a tongue on one end of each section engaged in a socket in the abutting end of an adjacent section.

Heretofore wall coping of this type has been made commercially in which the socket is provided in an outwardly flared formation at one end of each coping section into which a plain end of each coping section is adapted to fit. This type of coping accordingly has a series of spaced projections along the top of the wall.

It is desirable to have a wall coping which is smooth and free of such spaced projections at the joints between the coping sections and it has been proposed in the past to provide such coping in which the coping sections are formed so as to ship-lap at the joints. In clay copings, however, this is objectionable since the coping sections must be made too thick to provide sufficient material in the ship lap formations to be economically and effectively fired in the manufacture of such coping.

One purpose of the present invention, therefore, is to provide wall coping of the type described with improved tongue and socket joint formations whereby a smooth joint is provided while maintaining the coping thickness desirable for economical and effective manufacture.

Another purpose of the invention is to provide improved means in sectional wall coping for more effectively securing the coping sections on a wall, a means which while capable of utilization in different types of wall copings, is especially advantageous in the coping structure described in the preceding paragraph.

The foregoing and other purposes of the invention are attained in the wall coping illustrated in the accompanying drawing and described below. It is to be understood that the invention is not limited to the specific form thereof illustrated and described.

Of the accompanying drawing,

Figure 1 is a plan view, partly broken away and in section, of a wall coping embodying the invention;

Figure 2 is an elevation thereof partly broken away and in section;

Figure 3 is a perspective view of the tongue end of a coping section embodying the invention;

Figure 4 is an end view of the socket end of said coping section;

Figure 5 is a section on line 5—5 of Figure 2; and

Figure 6 is a section on line 6—6 of Figure 2.

Referring to the drawing, the numeral 10 designates a wall coping section of fired clay which may be of the usual thickness for economical and effective firing and which may be of concavo-convex formation in section as shown, a concave 60 groove extending along the under side thereof, and which may be provided with depending flanges 11, 11 for overlapping the joint between the coping and the wall on which it is applied.

Each section has at one end thereof a portion 65 12 extending inwardly of the groove on the under side of the coping provided with an extended tongue 13, shaped to fit into the said groove at the opposite end of an adjoining coping section, the said opposite end of each section being left 70 open and unobstructed to provide a socket for said tongue. The width of this tongue is such that the depending flanges 11 of an adjoining section will clear the tongue and fit in juxtaposition with the depending flanges of an adjoining 75 section.

In the groove on the under side of each coping section there are formed ribs 14, 14 for interlocking each section on the top of a wall. These ribs do not extend all the way to the socket end 80 of the coping section, being cut-away as at 14^a, 14^a (Fig. 2) to clear the tongue of an adjacent section. These ribs are preferably placed comparatively close to the flanges 11 and the sides thereof opposite the inner faces of the flanges 85 are undercut as shown, so that the coping sections may be jointed to the walls with cement or mortar as indicated at 15, 15 on which the coping sections are placed, the mortar flowing into the 90 spaces between the ribs 14 and the flanges 11 and dovetailing the coping sections to the top of a wall structure (see Figures 2 and 6).

The improved coping sections may be easily and effectively jointed to provide an improved joint preventing water from finding its way 95 downwardly into the wall structure. Cement or mortar is applied on top of the tongue 13 of a previously mounted section and upon application of a succeeding section to the wall is squeezed between the coping members and up into the joint 100 between the abutting ends of the coping sections above the tongue and down about the edges of the tongues between these and the flanges 11, 11 (see Figures 2 and 5).

Modifications of the invention may be resorted to without departing from the spirit thereof or the scope of the appended claims.

What is claimed is:—

1. A coping unit comprising a substantially flat body portion of arcuate cross-section and having 110

- longitudinally extending depending flanges along its opposite edges, depending ribs upon the under side of said body portion and extending longitudinally in spaced relation with respect to said flanges, said ribs terminating short of one end of said body portion, a depending wall at the opposite end of said body portion and with which the adjacent ends of said ribs are connected, and an arcuate longitudinally extending tongue on the outer end of said wall and disposed in a plane substantially beneath the under surface of said body portion.
2. A coping unit comprising a substantially flat body portion of arcuate cross-section and having longitudinally extending depending flanges along its opposite edges, depending ribs upon the under side of said body portion and extending longitudinally in spaced relation with respect to said flanges, said ribs terminating short of one end of said body portion and having the sides adjacent said flanges tapered inwardly from the latter toward said body portion, a depending wall at the opposite end of said body portion and with which the adjacent ends of said ribs are connected, and an arcuate longitudinally extending tongue on the outer end of said wall and disposed in a plane substantially beneath the under surface of said body portion.
3. A coping unit comprising a substantially flat body portion having longitudinally extending depending flanges along its opposite edges, a depending wall at one end of said body portion extending between said flanges, and a longitudinally extending tongue on the outer end of said wall and disposed in a plane substantially beneath the under surface of said body portion.
4. A coping unit comprising a substantially flat body portion having longitudinally extending depending flanges along its opposite edges, a depending wall at one end of said body portion extending between said flanges, depending ribs upon the under side of said body portion and extending longitudinally in spaced relation with respect to said flanges, and a longitudinally extending tongue on the outer end of said wall and disposed in a plane substantially beneath the under surface of said body portion.
5. A coping unit comprising a substantially flat body portion having longitudinally extending depending flanges along its opposite edges, a depending wall at one end of said body portion extending between said flanges, depending ribs upon the under side of said body portion and extending longitudinally in spaced relation with respect to said flanges, said ribs at one end being connected to the inner end of said wall and at the other end terminating short of the adjacent end of said body portion, and a longitudinally extending tongue on the outer end of said wall and disposed in a plane substantially beneath the under surface of said body portion.
6. A coping unit comprising a substantially flat body portion having longitudinally extending depending flanges along its opposite edges,

a depending wall at one end of said body portion extending between said flanges, depending ribs upon the under side of said body portion and extending longitudinally in spaced relation with respect to said flanges, the sides of the ribs adjacent said flanges being tapered inwardly from the latter toward said body portion, said ribs at one end being connected to the inner end of said wall and at the other end terminating short of the adjacent end of said body portion, and a longitudinally extending tongue on the outer end of said wall and disposed in a plane substantially beneath the under surface of said body portion.

7. A coping construction comprising units adapted to be laid in end to end abutting relation and having a substantially continuous unobstructed upper surface, each unit comprising a substantially flat body portion having depending flanges along its opposite edges which overlie the opposite wall surfaces and are spaced therefrom, depending ribs upon the under side of said body portion and extending longitudinally in spaced relation with respect to said flanges, said ribs being adapted to support said unit upon the top of the wall, said ribs at one end terminating short of the adjacent end of said body portion, a depending wall at the other end of said body portion extending between said flanges and with which the opposite ends of said ribs are connected, and a longitudinally extending tongue on the outer end of said wall and disposed in a plane substantially beneath the under surface of said body portion, said tongue being adapted for insertion into the end of an adjacent unit beneath the under surface thereof and in proximity to the free ends of said ribs.

8. A coping construction comprising units adapted to be laid in end to end abutting relation and having a substantially continuous unobstructed upper surface, each unit comprising a substantially flat body portion having depending flanges along its opposite edges which overlie the opposite wall surfaces and are spaced therefrom, depending ribs upon the under side of said body portion and extending longitudinally in spaced relation with respect to said flanges, the sides of said ribs adjacent said flanges being tapered inwardly from the latter toward said body portion, said ribs being adapted to support said unit upon the top of the wall, said ribs at one end terminating short of the adjacent end of said body portion, a depending wall at the other end of said body portion extending between said flanges and with which the opposite ends of said ribs are connected, and a longitudinally extending tongue on the outer end of said wall and disposed in a plane substantially beneath the under surface of said body portion, said tongue being adapted for insertion into the end of an adjacent unit beneath the under surface thereof and in proximity to the free ends of said ribs.
